CLAIM

The ornamental design for a phototherapy patch storage box, as shown and described.

DESCRIPTION

FIG. 1 is a top perspective view of a phototherapy patch storage box in an open position;

FIG. 2 is a front view of the phototherapy patch storage box thereof;

FIG. 3 is a back view of the phototherapy patch storage box thereof;

FIG. 4 is a left side view of the phototherapy patch storage box thereof;

FIG. 5 is a right side view of the phototherapy patch storage box thereof;

FIG. 6 is a top view of the phototherapy patch storage box thereof;

FIG. 7 is a bottom view of the phototherapy patch storage box thereof;

FIG. 8 is a top perspective view of the phototherapy patch storage box in a closed position thereof;

FIG. 9 is a front view of the phototherapy patch storage box thereof in a closed position; and,

FIG. 10 is an in-use view of the phototherapy patch storage box thereof.

The broken line showing of the exemplary patch and controller in FIG. 10 depicts environmental structure of the in-use view and forms no part of the claimed design. The remaining broken lines in the drawings illustrate portions of the phototherapy patch storage box that form no part of the claimed design.
